(57) CLAIM

The ornamental design for a toilet brush holder, as shown and described.

DESCRIPTION

FIG. 1 is a rear, top, left perspective view of a toilet brush holder showing my new design;

FIG. 2 is a front, bottom, left perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the toilet brush holder that form no part of the claimed design.
